UNITED STATES PATENT OFFICE.

HENRY M. CROWTHER, OF KINGMAN, ARIZONA.

ROTARY-VALVE GAS-ENGINE.

1,272,630.

Specification of Letters Patent. Patented July 16, 1918.

Application filed March 14, 1918. Serial No. 222,484.

To all whom it may concern:

Be it known that I, HENRY M. CROWTHER, a citizen of the United States, residing at Kingman, in the county of Mohave and State of Arizona, have invented new and useful Improvements in Rotary-Valve Gas-Engines, of which the following is a specification.

My object is to make an improved rotary valve gas engine and my invention consists in the novel features herein shown, described and claimed.

Figure 1 is a central sectional elevation on a line parallel with the crank shaft.

Fig. 2 is a fragmentary sectional detail on the same plane as Fig. 1 and showing the omission of the rotating cylinder lining.

Fig. 3 is a horizontal cross-section on the line 3—3 of Fig. 1.

Fig. 4 is a perspective of the mutilated driving gear and balancing cam.

Fig. 5 is a perspective of the driven gear with which the mutilated gear and cam co-operate.

Fig. 6 is a perspective of the rotating valve and rotating cylinder lining.

Fig. 7 is a horizontal cross-section on the line 7—7 of Fig. 1.

Fig. 8 is a diagram of the moving parts in position with the exhaust port open.

Fig. 9 is a diagram of the moving parts in position with the intake port open.

Fig. 10 is a diagram illustrating the operation of the mutilated driving gear, the operating driven gear, and the balancing cam for holding the driven gear while the mutilated gear is out of mesh.

In the drawings I have shown a single cylinder construction and it is to be understood that any desired number of cylinders may be used.

The crank shaft 1 is mounted in a crank case 2 and carries a fly wheel or pulley 3. The piston cylinder case 4 extends upwardly from the crank case 2 and is secured removably in place by bolts 5. The piston rod 6 is connected to the crank shaft 1 by a separable bearing 7 and extends upwardly through an opening 8 in the crank case 2 and is connected to and operates the piston 9. The cylinder case 4 is provided with a water jacket 10. In Fig. 1 the piston 9 operates in an intermittently rotating cylinder lining 11, said lining being mounted in the cylinder case 4. In Fig. 2 the rotating lin-

ing 11 is omitted and the case 4 is machined to fit the piston 9.

Motor fuel is supplied to the explosion chamber 12 through an intermittently rotating valve 13 formed integral with the intermittently rotating cylinder lining 11, as shown in Fig. 1, or operating independently, as shown in Fig. 2.

The cylinder lining 11 is an integral cylinder internally machined to fit the piston 9 and externally machined to form winding bearing faces 14 to fit the bore 15 in the cylinder case 4, there being winding clearance spaces 16 between the bearing faces 14. The bearing faces 14 and the clearance spaces 16 are like a coarse high pitch screw-thread extending from the lower edge of the lining to the upper edge and serve to elevate oil which is splashed into the lower end of the case 4 from the oil supply 17 in the crank case 2.

The details of the intermittently rotating valve 13 are as follows: In constructing the cylinder lining 11 a head 18 is provided, said head being formed integral with one end of the lining and there being diametrically arranged ports 19 and 20 through the head. The edges 21 and 22 of the port 19 and the edges 23 and 24 of the port 20 are on radial lines and extend from the hub 25 of the head to the inner face of the lining 11. A valve stem 26 extends upwardly from the hub 25 at the axial center of the head 18. Screw-threads 27 are formed on the upper part of the stem 26 and the extreme upper end 28 of the stem is machined and provided with a key-seat 29.

When it is desired to provide a rotary valve 13 without the cylinder lining 11 the cylinder lining is simply omitted from the casting or cut away.

The cylinder case 4 is provided with a head 30, there being a central bore 31 in the head to receive the valve stem 26, the upper end of the bore 31 being enlarged to form a spring seat 32 to receive the expansive coil spring 33. A large washer 34 is placed upon the stem 26 against the spring 33 in position to cover the spring seat 32, and a nut 35 is screwed upon the threads 27 against the washer 34.

The lower face of the head 30 is machined and the upper face of the valve head 18 is correspondingly machined to make a good fit, and the tension of the spring 33

is exerted to hold the valve head 18 against the case head 30 and prevent rattling.

An intake port 36 is formed through the head 30 and an exhaust port 37 is formed through the head 30 at right angles to the intake port. A carburetor 38 is connected to the intake port 36. A spark plug 39 is mounted through the case head 30 and a relief cock 40 is mounted through the case head diametrically opposite the spark plug.

The driven gear 41 comprises a hub 42 adapted to fit upon the machined portion 28 of the stem 26 and carry a spline or key, a web 43 extending from the hub 42, and bevel gear teeth 44 upon the outer rim of the web. The upper end of the hub 42 is closed by a cam head 45, and a transverse diametrically arranged cam slot 46 is formed in the upper face of this head, the ends 47 and 48 of the slot being flaring or rounded.

A gear case 49 is mounted upon the head 30, a gear 50 is fixed upon the crank shaft 1 inside of the crank case 2, and a countershaft 51 is mounted with its lower end extending through the crank case and connected to the gear 50 by a gear 52. The shaft 51 extends through the breather 53 in the crank case 2 and extends through a stuffing box 54 in the gear case 49, and a gear 55 is fixed upon the upper end of the shaft 51 in the gear case. A second countershaft 56 is mounted horizontally in the gear case 49 and a gear 57 is fixed upon the second countershaft 56 to be driven by the gear 55 upon the first countershaft 51. The gears 50 and 52 are preferably spiral gears set at right angles to each other, and the gears 55 and 57 are also spiral and set at right angles to each other.

40 The gear case 49 is adapted to be filled to any desired extent with suitable lubricating oil through a breather and filler cap 58, and a splasher 59 is fixed upon the shaft 56 for circulating the oil.

45 The mutilated driving gear 60 is fixed upon the second countershaft 56 and has teeth 61 extending approximately one-half the way around its periphery, said teeth being adapted to mesh with the teeth 44 upon the driven gear 41, and the balancing cam 62 is fixed upon the hub 63 of the gear 60, said cam 62 being semi-disk shaped and the cam edge 63 extending through slightly more than half a circle, said cam edge being 55 diametrically opposite the teeth 61 and adapted to engage in the slot 46, so as to hold the valve 13 from rotating during substantially half a revolution of the shaft 56. The ratio of speed between the crank shaft 1 and the second countershaft 56 is two revolutions of the crank shaft to one revolution of the countershaft. Referring to Fig. 10, the parts are so arranged that the forward end of the cam edge 63 will enter the flaring end of the slot 46 before the rear

teeth upon the mutilated gear 60 pass out of mesh with the teeth upon the driven gear 41, so as to hold the valve 13 from spinning and so as to properly time the opening and closing of the inlet and exhaust ports, and 70 in a like manner the rear end of the cam edge 63 will not entirely pass out of the slot 46 until the forward teeth 61 again mesh with the teeth 44. I consider this intermittent motion between the constantly rotating 75 crank shaft and intermittently rotating valve of great importance. The intermittently rotating cylinder lining is also of great importance.

Two revolutions of the crank shaft make 80 a cycle of the engine. One half of a revolution of the valve makes a cycle of the engine. The two ports in the valve are used alternately. One port makes a cycle of the engine and the other port makes the next cycle 85 of the engine, and so on. The valve stem is practically still during the compression and explosion impulses and the valve is under very little pressure when it is being moved.

In the practical operation, oil is placed in 90 the crank case 2 and in the gear case 49. The operation of the crank shaft 1 carrying the piston rod 6 and separable bearing 7 will throw oil up into the lower end of the cylinder case 4. The operation of the crank shaft 95 will intermittently rotate the cylinder lining 11 and the winding bearing faces 14 upon the cylinder lining will carry oil upwardly between the cylinder lining and the case 4 to the rotating valve 13, thereby lubricating the valve and cooling the lining and valve. The ports 19 and 20 in the valve 13 are diametrically arranged, whereas the intake port 36 and exhaust port 37 are arranged at right angles to each other. When 100 a port 19 or 20 has passed the intake port 36, as shown in Fig. 3, the explosive charge in the chamber 12 will be ignited through the port by the spark plug 39. The next stroke of the piston will bring a port 19 or 105 20 into registry with the exhaust port 37. Continued operation will bring the same port into registry with the intake port 36 and the chamber 12 will be recharged and these operations continue. The cam edge 110 63 holds the valve 13 and the cylinder lining 11 from spinning between the operations of the mutilated gear 60 upon the gear 41. The operation of the splasher 59 keeps the gears 115 within the gear case 49 lubricated.

120 Among the many advantages, attention is called to the fact that the faces of the valve parts operate by sliding rotating contact and are self-grinding, that no carbon can accumulate upon the faces of the valve parts, that there are no dead explosion recesses, that the whole explosive force is exerted upon the piston face thus saving fuel, that the scavenging operation is more complete due to the fact that the face of the piston may move 125 130

close to the lower face of the valve, that the valve parts open and close quickly, that the parts are not calculated to wear loose or rattle, that it is easier to adjust the timing accurately, that the rotation of the cylinder lining will constantly grind the working faces of the lining and piston and make the wear more even, that the rotating cylinder lining will improve the lubrication of the valve and assist in cooling the cylinder and valve, and that there are fewer working parts, requiring less waste of power than in the old puppet valve construction.

Various changes may be made in the details of construction without departing from the spirit of my invention as claimed.

I claim:

1. A rotary valve gas engine comprising a crank case, a crank shaft in the crank case, a cylinder case extending from the crank case and having a head; there being an exhaust port and an intake port through the head; a valve rotatably mounted against the inner face of the head and having ports adapted to register with the exhaust port and the intake port, a cylinder lining extending from the valve and rotatably mounted in the cylinder case; there being winding bearing faces upon the periphery of the lining and fitting the case; a stem extending from the valve through the head, a driven gear upon the stem, a gear upon the crank shaft, a countershaft, a gear upon the countershaft meshing with the gear upon the crank shaft, a second countershaft, gears connecting the first countershaft to the second countershaft, a mutilated gear upon the second countershaft adapted to mesh with the driven gear upon the stem, a head extending from the hub of the driven gear and having a transverse slot, and a balancing cam rigid with the mutilated gear and diametrically opposed and adapted to engage in the slot to hold the valve while the mutilated gear is out of mesh.

2. In a rotary valve gas engine, a piston cylinder case having a head provided with an exhaust port and an intake port, a valve fitting against the inner face of the head and having ports adapted to register with the exhaust port and intake port, a stem extending from the valve through the head, a piston cylinder lining extending from the

valve and having winding bearing faces fitting the case, a driven gear fixed upon the stem, a mutilated driving gear mounted to mesh with the driven gear, a head rigid with the driven gear and having a transverse slot, a semi-disk shaped balancing cam rigid with the mutilated gear and having an edge adapted to fit in the slot to hold the valve from rotating when the mutilated gear is out of mesh, and means for driving the mutilated gear in time with a crank shaft.

3. In a rotary valve gas engine, a piston cylinder case having a head provided with an exhaust port and an intake port, a valve fitting against the inner face of the head and having ports adapted to register with the exhaust port and intake port, a stem extending from the valve through the head, a driven gear fixed upon the stem, a mutilated driving gear mounted to mesh with the driven gear, a head rigid with the driven gear and having a transverse slot, a semi-disk shaped balancing cam rigid with the mutilated gear and having an edge adapted to fit in the slot to hold the valve from rotating when the mutilated gear is out of mesh, and means for driving the mutilated gear in time with a crank shaft.

4. A rotary valve gas engine comprising a crank case, a crank shaft mounted in the crank case, a piston cylinder case extending from the crank case, a piston in the piston cylinder case and operatively connected to the crank shaft, a gear case mounted upon the cylinder case, a countershaft extending from the crank case into the gear case, gears connecting the crank shaft to the countershaft, a second countershaft in the gear case, gears connecting the second countershaft to the first countershaft, a rotary valve construction in the cylinder case, a stem extending from the valve through the head of the cylinder case, a driven gear upon the stem, a mutilated gear upon the second countershaft and adapted to mesh with the driven gear intermittently, a head rigid with the driven gear and having a transverse slot, and a semi-disk shaped balancing cam rigid with the mutilated gear and adapted to engage in the slot.

In testimony whereof I have signed my name to this specification.

HENRY M. CROWTHER.
